Orrin R. Haight,

By Thomas G. Orwig, Atty.

UNITED STATES PATENT OFFICE.

ORRIN R. HAIGHT, OF OSAGE, IOWA.

BEDCLOTHES-CLAMP.

SPECIFICATION forming part of Letters Patent No. 426,011, dated April 22, 1890.

Application filed October 29, 1889. Serial No. 328,605. (No model.)

To all whom it may concern:

Be it known that I, ORRIN R. HAIGHT, a citizen of the United States of America, and a resident of Osage, in the county of Mitchell 5 and State of Iowa, have invented a new and useful Bedclothes-Clamp, of which the following is a specification.

My object is to prevent the care and anxiety incident to colds and sickness resulting from 10 children lying uncovered while asleep, and to provide means for securely fastening covers over them, so that they cannot displace them by the movements of their bodies.

My invention consists in an adjustable 15 clothes-clasping device adapted to be attached to a bed and operated, as hereinafter set forth, pointed out in my claims, and illustrated in the accompanying drawings, in which—

Figure 1 is a perspective view of a bed or 20 child's crib showing my invention applied as required for practical use. Fig. 2 is an enlarged side view of the device, from which a part is broken away to disclose a ratchet and pawl. Fig. 3 is an edge view of the complete 25 device. Fig. 4 is a perspective view of a metal loop adapted to connect the device with a bed loop by means of an elastic strap.

A is the body and main portion of the device in the form of a straight metal bar that 30 has an integral loop B at one end and is bifurcated at the other end and adapted to produce, in combination with another part, a hinge-joint.

C is a metal clasp curved at one end and 35 fitted into the bifurcated end and socket of the piece A, and pivoted thereto by means of a screw or rivet d. The extremity of the curved end is a segment provided with ratchet-teeth.

g is a pawl pivoted in a slot formed in the 40 edge or back of the piece A in such a manner that it will engage the teeth on the end of the piece C, as clearly shown in Fig. 2. The free end of the pawl is adapted in form to be engaged by a person's thumb, to be pressed downward for the purpose of disengaging the other end from the ratchet-teeth, as required, to allow the piece or clasp C to be adjusted.

h is a coiled spring placed between the pawl 45 and the part A in such a manner that it will

in its normal condition keep the pawl engaged with the ratchet-teeth and the clasp rigidly locked thereby to the part A.

The inside face of the clasp C is preferably convex, and its free end terminates in a thumb- 55 rest in such a manner that when a person's fingers clasp the part A the thumb can be pressed upon the free end of the part C to inclose and compress and fasten parts of bedclothes placed between the two pieces A and C, so that when pressure upon the pawl is relaxed the complete device will be securely fastened to such bed-covering.

J represents a flexible strap, preferably elastic webbing, fixed to the loop B by stitching 60 or in any suitable way.

To apply the invention to a bed, I fix two or more of the metal loops K (shown in Fig. 4) to the inside of each rail of the bed or crib and attach the ends of the straps J thereto, 70 as illustrated in Fig. 1, in such a manner that the quilts, blankets, or other covering thereon can be readily clasped and securely held, as required, to prevent the person underneath from accidentally getting uncovered. 75

I claim as my invention—

1. A device for holding bedclothes, consisting of a metal bar having an integral loop at one end and a flexible strap attached to said loop, a curve at the other end of the bar, and a 80 clasp having a ratchet-face on its end hinged to the curved end of the bar, and a spring-actuated pawl attached to the bar to engage the ratchet on the end of the clasp, to operate in the manner set forth.

2. The bedclothes-clamp composed of the bar A, having a loop B at one end, a clasp C, hinged to its other end, a ratchet-face on the hinged end of the clasp, and a pawl g and spring h, attached to the bar, and a flexible 85 strap J, attached to the loop B, in combination with a loop K, fixed to a bedstead, substantially as shown and described, to be applied and operated in the manner set forth, for the purposes stated. 90

ORRIN R. HAIGHT.
